CLAIM

The ornamental design for a recessed lighting fixture with a sliding adjustment feature, as shown and described herein.

DESCRIPTION

FIG. 1 illustrates a side view of a recessed lighting fixture with a sliding adjustment feature, according to a first embodiment.

FIG. 2 illustrates a front view of the recessed lighting fixture, according to the first embodiment.

FIG. 3 illustrates a top-down plan view of the recessed lighting fixture, according to the first embodiment.

FIG. 4 illustrates a bottom-up view of the recessed lighting fixture, according to the first embodiment.

FIG. 5 illustrates a top-perspective view of the recessed lighting fixture, according to the first embodiment.

FIG. 6 illustrates a bottom-perspective view of the recessed lighting fixture, according to the first embodiment.

FIG. 7 illustrates a side view of a recessed lighting fixture with a sliding adjustment feature, according to a second embodiment.

FIG. 8 illustrates a front view of the recessed lighting fixture, according to the second embodiment.

FIG. 9 illustrates a top-down plan view of the recessed lighting fixture, according to the second embodiment.

FIG. 10 illustrates a bottom-up view of the recessed lighting fixture, according to the second embodiment.

FIG. 11 illustrates a top-perspective view of the recessed lighting fixture, according to the second embodiment; and, FIG. 12 illustrates a bottom-perspective view of the recessed lighting fixture, according to the second embodiment.

The broken lines in the drawings are for illustrative purposes only and form no part of the claimed design.
